(57) **CLAIM**

The ornamental design for a spa corner and wall assembly, as shown and described.

DESCRIPTION

FIG. 1 is a front right top perspective view of a spa corner and wall assembly according to the present invention.

FIG. 2 is a front view thereof.

FIG. 3 is a top view thereof.

FIG. 4 is a bottom view thereof.

FIG. 5 is a rear left perspective view thereof; and,

FIG. 6 is a front view similar to FIG. 2, but with the inventive spa corner and wall assembly shown as part of a complete spa.

The dash-dash broken lines in FIG. 6 showing an entire spa wall depict environmental subject matter that forms no part of the claimed design. The remaining dash-dash broken lines show portions of the spa corner and wall assembly that form no part of the claimed design. The dot-dash broken lines illustrate the boundaries of the spa corner and wall assembly and form no part of the claimed design.
